ADVERTISING DEVICE AND THE LIKE.

Application filed April 23, 1925. Serial No. 25,308.

This invention relates to improvements in advertising devices.

An object of this invention is to provide a device which is of simple construction and which can be cheaply operated.

It is a well known feature in advertising that in order to obtain good results, it is necessary to first attract the attention of the passing public. One of the most satisfactory methods for attracting attention is to stimulate curiosity.

It is therefore another object of this invention to provide a device which is so constructed as to have some moving parts which are so arranged that it is not apparent what causes these parts to move, thus stimulating curiosity as to how the device is operated.

With the foregoing and other objects in view which will be made manifest in the following detailed description and specifically pointed out in the appended claims, reference is had to the accompanying drawings for an illustrative embodiment of the invention wherein:

Figure 1 is a perspective view of the improved advertising device,

Fig. 2 is a vertical section taken upon the line 2—2 of Fig. 1, and

Fig. 3 is a vertical section taken on the line 3—3 of Fig. 1.

Referring to the accompanying drawings wherein similar reference characters designate similar parts throughout, the device consists of a container 10 having a cover 11 in which there is an aperture 12. Within the container 10 there is disposed a solenoid 13 which may be of any conventional construction and which is connected by wires to suitable binding posts 14. A U-shaped yoke 15 has one end secured upon the bottom of the container 10 as by bolts 16. The opposite end is disposed in approximately horizontal position and extends over the upper end of the solenoid 13, so as to act as a type of armature therefor. A socket 17 is mounted upon the upper end of the yoke 15, and a rod-like support 18 is disposed within the socket extending upwardly above the top of the container through the aperture 12. Upon the

rod-like support 18 there are one or more clamps or hooks 19, upon which indicia bearing elements 20 are mounted. These indicia bearing elements may be of any size or configuration and may bear any type of indicia desired. They are shown as provided with rubber bushings 21 which engage the hooks 19. Upon the under side of the cover 11 there is a spring 22 secured as by screws 23 and the spring has a pointed end 24 adapted to engage the upper end of the U-shaped yoke 15. A nut 25 is mounted in the cover 11 and a threaded bolt or stud 26 is threaded into the nut and is adapted to engage the top of the spring 22. This stud or bolt is shown as provided with a handle 27 which may have thereon a dial 28.

The operation of the device is as follows: In the preferred form of construction an alternating electric current supply is connected to the binding posts 14, so that the solenoid 13 will be energized by an alternating current. The solenoid being so energized causes the upper end of the U-shaped yoke 15 which acts as a spring to be attracted and repelled quickly, thus vibrating the spring provided by the yoke 15 and also the rod-like support 18. These vibrations imparted to the support 18 cause the elements 20 mounted thereon to rotate. It will be appreciated that the vibrations of the end of the yoke 15 depend upon the frequency of the current supplied to the solenoid 13. Usually the vibrations are of such a frequency that to the ordinary eye, the rod-like support 18 does not appear to vibrate in any manner, but appears to be perfectly stationary. The vibrations imparted to it, however, cause the discs or elements 20 to rotate.

A peculiar feature of the construction resides in the fact that certain of the discs 20 will rotate in one direction, whereas other discs will rotate in the opposite direction. The direction in which the discs or elements 20 rotate depends upon their location along the rod-like support 18. In this manner the lowermost disc 20 can be caused to rotate in one direction, and the uppermost disc 20 can be caused to rotate in the opposite direction.

If more than two discs or elements 20 are placed upon the rod-like support 18, which may be made considerably longer, a third disc, which is disposed above the uppermost disc shown, can be caused to rotate in the same direction as the lowermost disc. In this manner by placing a large number of elements upon the support, some of the elements will be caused to rotate in one direction and others will be caused to rotate in the opposite direction by the vibrations imparted to the support 18. The support 18 can be made of practically any material, but is preferably formed of glass, being in the form of a hollow glass tube. In obtaining the best results, a vacuum is formed within the tube, enabling the support 18 to be freely influenced by the vibrations imparted to it. When the device is in operation, the upper horizontal portion of the spring tends to vibrate about the point where the upper horizontal portion joins the vertical portion of the U-shaped spring. Also the vertical portion tends to vibrate and swing about the point where the vertical portion joins the lower horizontal portion of the U-shaped spring. Consequently, the end of the spring which is above the solenoid is influenced by two vibrations at right angles to each other, so that it vibrates on an arcuate path. This tends to set up a whip in the rod 18 so that this rod tends to bend at several points. If the clips 19 are positioned on the rod intermediate these points of bend, they will cause the discs to rotate. On the other hand, if the clips 19 are positioned at the points of bend, the discs 20 will not rotate. By having a long rod and properly positioning the clips, the discs can be caused to rotate in opposite directions. The spring 22, when pressed against the spring 15, serves to deepen the vibrations of this spring, decreasing their magnitude and accordingly causing a variation of speed of the discs. Making the tube of glass has another advantage in that it further tends to mystify the manner in which the elements 20 are caused to rotate. A person seeing the device in a show window, without knowing the construction of it, will usually attempt to find wires or the like in the support. A glass support clearly discloses that there are no wires or magnets which cause the discs or elements 20 to rotate. If the discs 20 are made of various sizes, the larger sized discs may have their speed of rotation decreased slightly because of the slight increase of air resistance. This variation of speed, however, is usually very small. The speed of the discs, however, can be varied considerably by varying the sizes of the apertures through them or varying the size of the aperture through the rubber bushing 21. Discs having a small aperture through them rotate much faster than the

discs having the larger apertures or rubber bushings. Preferably in using the device as an advertising device a large disc is used which has a larger aperture through it, and this disc carries indicia advertising various articles of merchandise or other information, it being understood that its rotation is slow enough so that the indicia can be read upon it. The other discs which may be smaller or have smaller apertures, causing higher speeds, may have suitable designs upon them which will serve to attract attention during their higher speeds of rotation. The handle 27 can be employed for increasing and decreasing the speeds of the discs on the support 18. By screwing down the stud 26, causing the spring 22 to have its point 24 engage or bear upon the upper end of the spring 17, the amplitude of the vibrations imparted to the support 18 can be varied. Such a variation in the amplitude in the vibrations imparted to the support 18 varies with the speed of rotation of the discs 20 thereon.

It will be understood that the specific manner of imparting vibrations to the support 18 is immaterial. Although I preferably employ the construction as shown which enables the use of alternating current, permitting the device to be used a considerable length of time for a small amount of cost, this means for vibrating the support 18 is not essential. If desired, the spring 22 and the spring 15 may be used as contacts forming a make and break contact for the solenoid 13, enabling direct current to be used. Other means for vibrating the support 18 can also be employed.

The advantage of this device in advertising resides in the fact that all parts with the exception of the discs 20, the hooks 19 and the support 18, are disposed within the container 10; and as there is no apparent means for causing the elements 20 to rotate, the construction stimulates curiosity.

It will be understood that the device as disclosed is not limited to be used for advertising purposes, but may also be used as a toy or as a game and is adapted for other uses as well.

It will be understood that various changes in the detail of construction may be made without departing from the spirit or scope of the invention as defined by the appended claims.

I claim:

1. An advertising device comprising a support, an element mounted upon said support so as to be rotatable thereon, a spring upon which said support is mounted, and means for vibrating said spring so as to vibrate said support and cause said element to move relatively to said support.

2. An advertising device comprising a support, an indicia bearing element mounted

upon said support so as to be rotatable thereon, and electro-magnetic means for vibrating said support so as to cause said indicia bearing element to rotate thereon.

3. An advertising device comprising a support, an indicia bearing element mounted upon said support so as to be rotatable thereon, a spring upon which said support is mounted, and electro-magnetic means for 10 vibrating said spring so as to vibrate said support and cause said element to rotate thereon.

4. An advertising device comprising a support, an indicia bearing element mounted 15 upon said support so as to be rotatable thereon, a spring upon which said support is mounted, electro-magnetic means for vibrating said spring so as to vibrate said support and cause said element to rotate 20 thereon, and means for varying the amplitude of the vibrations so as to vary the speed of rotation of said element.

5. An advertising device comprising a support, an indicia bearing element mounted 25 upon said support so as to be rotatable thereon, and electric means for vibrating said support so as to cause said indicia bearing element to rotate thereon.

6. An advertising device comprising a support, an indicia bearing element mounted 30 upon said support so as to be rotatable thereon, electric means for vibrating said support so as to cause said indicia bearing element to rotate thereon, and means for varying the amplitude of the vibrations so as 35 to vary the speed of rotation of said element.

7. An advertising device comprising a rod-like support, a spring upon which said support is mounted, a solenoid adjacent said 40 spring, means for supplying an alternating current to said solenoid, and an indicia bearing element mounted upon said support so as to be rotatable thereon, said solenoid being adapted to vibrate said spring and support 45 and cause said element to rotate thereon.

8. A device of the class described comprising an upright support, a horizontal arm 50 adjustably mounted upon said support, an element having an aperture therethrough through which said arm loosely extends, and means for vibrating said support so as to cause said element to rotate on said arm.

9. A device of the class described comprising an upright support, a horizontal 55 arm adjustably mounted upon said support, an element having an aperture therethrough through which said arm loosely extends, and electro-magnetic means for vibrating said support so as to cause said element to rotate 60 upon said arm.

10. A device of the class described comprising an angular spring having an upright portion and a substantially horizontal portion, an upright support mounted on the 65 horizontal portion, an arm carried by the

support, an element having an aperture therethrough through which the arm loosely extends, and means for vibrating the horizontal portion of the spring so as to vibrate the support and cause the element to rotate 70 upon said arm.

11. A device of the class described comprising an angular spring having an upright portion and a substantially horizontal portion, an upright support mounted on the 75 horizontal portion, an arm carried by the support, an element having an aperture therethrough through which the arm loosely extends, and a solenoid disposed adjacent the horizontal portion of the spring, said 80 solenoid being adapted when energized to vibrate the spring and support and cause said element to rotate on said arm.

12. A device of the class described comprising a U-shaped spring, a solenoid 85 arranged between the free ends of the spring, a support mounted upon one of the free ends of the spring, an arm carried thereby, and an element having an aperture therethrough through which the arm loosely extends, said 90 solenoid being adapted to vibrate said spring and support when energized to cause said element to rotate on said arm.

13. A device of the class described comprising a U-shaped spring, a solenoid 95 arranged between the free ends of the spring, a support mounted upon one of the free ends of the spring, an arm carried thereby, an element having an aperture therethrough through which the arm loosely extends, said 100 solenoid being adapted to vibrate said spring and support when energized to cause said element to rotate on said arm, a resilient part bearing upon that arm of the spring on which the support is mounted, and means 105 for varying the pressure at which the resilient part bears on the spring so as to vary the speed of rotation of said element.

14. A device of the class described comprising a U-shaped spring, a solenoid 110 arranged between the free ends of the spring, a support mounted upon one of the free ends of the spring, an arm adjustably mounted upon said support, an element having an aperture therethrough through which the 115 arm loosely extends, said solenoid being adapted to vibrate said spring and support when energized to cause said element to rotate on said arm.

15. A device of the class described comprising a U-shaped spring, a solenoid arranged between the free ends of the spring, a support mounted upon one of the free ends of the spring, a plurality of arms carried thereby, and a plurality of elements 120 each having an aperture therethrough through which the arms loosely extend, said solenoid being adapted to vibrate said spring and support when energized to cause said 125 elements to rotate on said arms.

16. A device of the class described comprising a solenoid, means providing an armature adapted to be actuated by the solenoid, a support mounted upon the armature, an arm carried by said support, and an element having an aperture therethrough through which the arm loosely extends, said

element being adapted to rotate upon said arm when said support and armature are vibrated.

10

In testimony whereof I have signed my name to this specification.

PETER J. KURTEN.
